United States Patent Office

Des. 177,014
Patented Mar. 6, 1956

177,014

TEXTILE FABRIC

William H. Carroll, Weehawken, N. J., assignor to Chicopee Mills, Inc., a corporation of New York

Application April 27, 1955, Serial No. 35,695

Term of patent 14 years

(Cl. D92—1)

Fig. 1

Fig. 2

Fig. 1 is a plan view of a textile fabric showing my new design; and Fig. 2 is a schematic view on an enlarged scale depicting the relationship of the various components of the weave.

I claim:

The ornamental design for a textile fabric, as shown.
